DISPENSING TUBE

Raymond J. Short, Nutley, N. J., assignor, by
mesne assignments, to Lusteroid Container
Company, Inc., Maplewood, N. J., a corpora-
tion of New Jersey

Application June 18, 1931. Serial No. 545,292

3 Claims. (Cl. 221—60)

This invention relates to a dispensing tube which is used as an ordinary collapsible tube and which includes an ordinary collapsible tube which is stiffened by a coating or an outside tube of material stiffer than the metal of the tube. A number of various substances can be used as the coating or outer tubing and it can be applied by brushing, spraying or dipping. I find that celluloid is the best material so far used and the most economical and quickest way to apply is by dipping the tube in the celluloid. The tube is preferably coated as soon as it has been made and while it is still symmetrical. This coating holds the tube to its shape during the subsequent handling when filling and during transportation and selling.

The dispensing tube has an improved appearance over the ordinary metal tube because it can be made all one color when using translucent or solid color covering or it can give a protective and reflective covering to a metal tube when the covering is plain or colored transparent material. In case the metal tube is printed upon or is ornamented the outer covering serves to protect the printing.

Another advantage of this dispensing tube is that by applying a solvent to the covering when of celluloid, especially when the covering extends part way up on the inside of the tube, a perfectly tight closing is possible in the folding and sealing of the tube after filling.

My invention also embraces the method of covering a thin collapsible metal tube with a stiffening cover by applying the cover to it by dipping or in any other manner.

A tube to illustrate one form of the new article is shown in the drawing. Figure 1 is a view, one half in section and one half in elevation, of a tube. Figure 2 is a section on line 2—2 in Figure 1.

As an inner tube or member 10, I provide a thin metal collapsible tube. These are now commonly used in dispensing creams and liquids and are usually made with a large end 11 used in filling and later sealed. The other end is provided with a shoulder 12 from which projects the nozzle 13 having a discharge opening 14. The nozzle is closed by a suitable cap (not shown) which is usually screwed down over the nozzle 50 which is provided with a screw-thread 16 to receive the threads of the cap.

On the outside of this pliable inner tube I place another tube 17. The outer tube is made of material stiffer than the inner tube and is 55 more resistant to distortion of a permanent na-

ture. Many materials can be used for this outer tube but I find celluloid an excellent material. A thin outer tube of celluloid resumes its shape after compression and always presents a neat outside appearance even when the inner or collapsible tube has but little material left in it. This is in marked contrast with the usually partially or nearly empty collapsible tube as now made. It is misshapen and any directions or other printed matter on the tube is so compressed and wrinkled as to be of no value. In my improved tube this is not the case. The tube retains for the most part, a symmetrical form, and when the outer tube is affixed to the inner tube it pulls it out into shape after it has been squeezed.

The outer tube 17 can be made as a separate tube and then placed around the inner tube either in the absence or presence of heat. The usual way is to spray the material on or to dip the collapsible tube 10 into a solution. Celluloid after, say, two dippings provides a good outer covering on the inner tube. This dipping is done while the inner tube is new and cylindrical. The outer tube can be carried over the shoulder 12 at 18 and may also be extended over the 70 thread 16 as at 19.

The lower part of the outer tube can be extended over for a short distance on the inside of the inner tube as at 20. This aids in sealing as the material can be treated with a solvent in 85 sufficient quantity to provide a tight joint and seal when the tube is pressed flat and folded over after filling.

The outer tube can be made as a separate article and then applied to the inner tube and in 90 such construction it is held firmly in place by the fold at the bottom when the tube is closed and by the shoulder part 18 at the top of the tube.

A transparent outer tube either of clear or 95 colored transparent nature or one made translucent gives a permanent protection against oxidation or dulling of the metal inner tube and also contributes to the tube a pleasing reflective appearance. The article is of a highly ornamental appearance.

I claim:

1. A dispensing receptacle comprising a thin non-resilient collapsible tube of metal and a second tube of celluloid affixed to the outside of 105 the collapsible tube, the celluloid tube causing the collapsible tube to resume its normal shape when squeezing pressure is released, the collapsible tube thus forming a lining to the resilient celluloid tube.

2. A dispensing receptacle adapted to be collapsed for expelling contents, comprising a tube of celluloid stiff enough to resume its shape after compression and an inner tube of thin non-resilient metal, said tubes being secured together whereby the celluloid tube causes said inner tube to be distended in normal condition and said celluloid tube is shielded from contact with the contents of the tube. 80
- 10 3. A dispensing receptacle adapted to be collapsed for expelling contents, comprising a tube of celluloid stiff enough to resume its shape after compression and an inner tube of thin non-resilient metal, said tubes being secured together whereby the celluloid tube causes said inner tube to be distended in normal condition and said celluloid tube is shielded from contact with the contents of the tube. 85
